UNITED STATES PATENT OFFICE.

CHARLES FREDRICK MITCHELL, OF BALTIMORE, MARYLAND.

NON-REFILLABLE BOTTLE.

SPECIFICATION forming part of Letters Patent No. 703,944, dated July 1, 1902.

Application filed June 4, 1901. Serial No. 63,069. (No model.)

To all whom it may concern:

Be it known that I, CHARLES FREDRICK MITCHELL, a citizen of the United States, residing at Baltimore, in the State of Maryland, have made certain new and useful Improvements in Non-Refillable Bottles, of which the following is a specification.

My invention is an improvement in non-refillable bottles, and has for an object to provide an improved construction of non-refillable bottle in the use of which it will be necessary to break off the end of the neck of the bottle before the contents can be poured off; and the invention consists in certain novel constructions and combination of parts, as will be hereinafter described and claimed.

In the drawings, Figure 1 is a sectional view of a portion of a bottle embodying my invention. Fig. 2 is a cross-section on about line 2 2 20 of Fig. 1. Fig. 3 is a top plan of the bottle. Fig. 4 is a detail longitudinal section of the neck of the bottle. Fig. 5 is a detail sectional view of the sealing-plug with the attached locking-bails, and Fig. 6 is a detail side view 25 of the sealing-plug.

The bottle A may be of any suitable design or capacity and is provided with the neck B, which is formed with the main portion C and the end portion D, which is designed to be 30 broken from the portion C when it is desired to dispense the contents of the bottle. At the juncture of the sections D and C, I provide within the neck a groove or chamber E, opening into the neck of the bottle and adapted to 35 receive the bails on the sealing-plug, as presently described. I provide surrounding such chamber E a weakened point at F, so the part D can be readily broken off the end of the neck. The sealing-plug I may be of any suitable 40 material and form fitted to the neck of the bottle and preferably consists of a body I', having a groove I² to receive a rubber or other gasket and provided near its upper end with a groove I³ for the locking-bails J, from which 45 groove I³ extends an opening or socket I⁴ for the ends J' of the bails J. These bails J are preferably resilient, and they and the plug I are so formed that the bails may be turned before the plug is pushed home to a position 50 opposite the groove I³, so they may be pressed into such groove as the plug is pushed home until the bails come opposite the groove or

chamber E, when they will spring outward into such chamber, as shown in Fig. 2, and operate to lock the plug in place.

55

Now in order to dispense the contents of the bottle it will be necessary to break the end section D off the body-section C of the neck, exposing the bails J, which may then be turned to the position shown in Fig. 5 and employed 60 as handles in drawing the sealing-plug out of the neck of the bottle. It will be noticed that access to the contents of the bottle can only be had by breaking the neck of the bottle, as before described, thus mutilating the bottle 65 so it cannot be wrongfully reused.

To guard the neck of the bottle, I provide the guard-bails K and L, which are provided with the cross-bars extending over the neck of the bottle and interlocked at L', as shown in 70 Figs. 2 and 3, and are provided with the depending arms extending below the weakened point F of neck and having at their lower ends inturned arms K² and L², which extend beneath the shoulder M, such bails operating 75 to protect the lateral chamber and upper portion of the neck of the bottle, as will be understood from Figs. 1 and 3. When desired, the ends of the arms K² and L² may be prolonged circumferentially beneath the shoulder M, as shown at K³ and L³ in Fig. 3.

Having thus described my invention, what I claim as new, and desire to secure by Letters Patent, is—

1. A non-refillable bottle substantially as 85 described having its neck composed of upper and lower sections weakened at the juncture of such sections and provided internally with a lateral groove or chamber, the plug fitting in said neck and provided with a groove for 90 the locking-bails and with a socket leading from such groove for the ends of the bails, and the locking-bails having their ends seated in said sockets and arranged to be compressed entirely within the outer circle of the 95 plug and to spring outwardly into locking engagement within the lateral groove or chamber within the neck substantially as set forth.

2. The combination of the bottle, the plug having circumferential grooves and provided 100 at the ends thereof with sockets, and the bails having their body portions fitted to be incased in the grooves of the plug and their ends inturned and fitting in all positions of the bails

in the sockets at the ends of said grooves, substantially as set forth.

3. A non-refillable bottle comprising the neck the plug fitted to close said neck and the 5 locking-bails carried by the plug and pivotally connected at their ends therewith whereby they may be adjusted to lock the plug in the bottle-neck or to position to serve as handles for withdrawing the plug substantially 10 as set forth.

4. The combination of the bottle having an

external downwardly-facing shoulder and the guards extended over the ends of the neck at right angles to each other, and having their side bars provided at their lower ends with 15 practically rigid arms projecting beneath and extended circumferentially under the shoulders of the neck, substantially as set forth.

CHARLES FREDRICK MITCHELL.
